UNITED STATES PATENT OFFICE.

GEORGE C. KOTRBA, OF CHICAGO, ILLINOIS, ASSIGNOR OF ONE-HALF TO THOMAS E. WEAVER, OF CHICAGO, ILLINOIS.

WRENCH.

1,378,035.

Specification of Letters Patent. Patented May 17, 1921.

Application filed July 12, 1920. Serial No. 395,594.

To all whom it may concern:

Be it known that I, GEORGE C. KOTRBA, a citizen of the United States, and a resident of Chicago, in the county of Cook and State of Illinois, have invented a new and Improved Wrench, of which the following is a description.

This invention relates to improvements in wrenches, an object of the invention being 10 to provide a wrench which will be capable of quick adjustment and at the same time capable of absolutely accurate adjustment so that it may be adjusted to fit any size nut.

The principal difficulty with most wrenches 15 which have a quickly adjustable movable jaw is that the two jaws cannot be made to conform to the shape of any size nut. There is always a bit of play in the movable jaw. My invention overcomes this 20 fault.

A further object is to provide a wrench which will be simple and strong in construction and practical and durable in use.

With these and other objects in view the 25 invention consists in certain novel features of construction and combinations and arrangements of parts as will be more fully hereinafter described and pointed out in the claims.

30 In the accompanying drawings—

Figure 1 is a view in side elevation with parts broken away of my improved wrench;

Fig. 2 is a view in front elevation partly in section on the line 2—2 of Fig. 1;

35 Fig. 3 is a view in rear elevation;

Fig. 4 is a sectional view on the line 4—4 of Fig. 1.

Referring in detail to the drawings my improved wrench comprises a shank 1, a 40 fixed jaw 2 on the end of the shank, a handle 3 which may be of any approved kind and may be secured on the shank in any approved manner, and a movable jaw 4 which is slidably mounted on the shank.

45 A collar or boss 5 is located around the shank 1 adjacent the handle 3 and the boss 5 is made with a perforated lug 6, the perforation serving to guide an adjusting screw 7.

50 The jaw 4 is made with an integral boss 8 which is recessed in its under face to provide mounting for the end of the screw 7. The screw 7 is formed with an annular groove 9, and a pin 10 projected in the boss

8 engages in the groove 9 permitting turning movement of the rod but locking the rod against longitudinal movement.

The screw 7 constitutes in effect a rack in addition to its function as an adjusting screw and meshes with a pinion 11 mounted on a pin 13 in a recess 12 in the shank 1. A locking dog 14 is mounted in the recess 12 of shank 1 and pivotally supported between its ends on a pin 15. One end of the dog projects through a slot 12' in boss 5 as shown at 17 in convenient position for operation, and the inner end of the dog is pressed into engagement between the teeth of pinion 11 by means of a spring 16. It will be readily seen that by moving the 65 dog 14 out of engagement with the pinion 11 the operator may grasp the movable jaw 4 and move it quickly up or down on the shank.

When the dog 14 is released from the pinion 11 it permits a quick adjustment of the movable jaw, the screw 7 operating as a rack in engagement with pinion. This adjustment cannot be fixed exactly until the pinion is locked by the dog, when the screw 80 can be turned as much as desired to accurately make and hold the adjustment.

To facilitate the turning of the screw I provide on the free end thereof a milled enlargement 18 so that after the jaw 4 has 85 been moved as close as possible to the nut, by its quick sliding movement, the dog is permitted to lock the pinion and the screw 7 turned to further adjust the position of the jaw, the pinion acting as a thread and 90 engaging the threaded portion of the screw.

The operation will be readily understood. To engage a nut with a wrench the operator grasps the wrench with one hand and operates the finger 17 to move the dog 14 95 out of engagement with the pinion 11. The jaw 4 is moved to the desired position and the dog 14 is allowed to spring back into locked engagement with the pinion. If further adjustment is necessary it may be had 100 by turning the screw 7 as above pointed out.

While I have illustrated a preferred embodiment of the invention, it is obvious that various slight changes and alterations might be made in the general form of the parts 105 described without departing from my invention and hence I do not limit myself to the precise details set forth but consider myself

at liberty to make such slight changes and alterations as fairly fall within the spirit and scope of the appended claims.

Having thus described my invention, I

5 claim:—

1. A wrench comprising a shank, a fixed jaw on the shank, a movable jaw on the shank, a screw secured to the movable jaw, a pinion mounted in the shank meshing with 10 said screw and a spring-held dog normally locking the pinion against movement.

2. A wrench comprising a shank, a fixed jaw on the shank, a movable jaw on the shank, a boss integral with the movable jaw, 15 a screw having rotary mounting in the boss and forming a rack, a pinion mounted in the shank and meshing with the screw, a spring-

held dog normally locking the pinion against movement, and means whereby said movable jaw may be adjusted whether said 20 pinion is locked or unlocked.

3. A wrench comprising a shank, a fixed jaw thereon, a movable jaw thereon, a boss integral with the movable jaw, a screw having rotary mounting in said boss and forming a rack, a perforated fixed boss on the shank forming a guide for said screw, a pinion mounted in the shank meshing with said screw, means for locking the pinion against movement whereby said screw may be adjusted by a longitudinal and also by a turning movement of screw to control the position of said movable jaw.

GEORGE C. KOTRBA.
